UNITED STATES PATENT OFFICE.

LEWIS WORTHINGTON APPLEMAN, OF CARL JUNCTION, MISSOURI.

DRILL-RIG.

1,078,481.

specification of Letters Patent. Patented Nov. 11, 1913.

Application filed November 17, 1910. Serial No. 592,878.

To all whom it may concern:

Be it known that I, LEWIS W. APPLEMAN, a citizen of the United States, residing at Carl Junction, in the county of Jasper and State of Missouri, have invented a new and useful Drill-Rig, of which the following is a specification.

This invention has relation to drill rigs and consists in the novel construction and arrangement of its parts as hereinafter shown and described.

The object of the invention is to provide a drill rig in which is used a comparatively short metallic cable trained over sheaves, some of which are located upon a walking beam, in such manner that the dependant end of the said cable may be reciprocated vertically as the walking beam oscillates. Means is provided for shortening or lengthening the said cable and for maintaining the same at an adjusted length. A clamping device is carried by the said cable and is adapted to engage a relatively long hemp or Manila cable of the usual form to which the drilling tool is attached.

In the accompanying drawing: Figure 1 is a side elevation of the drill rig and Fig. 2 is a top plan view of the same. Fig. 3 is a detail view of a part of the rig.

The drill apparatus to which the rig is applied consists of the usual wheel mounted platform 1 upon which is located a samson post 2. A derrick 3 of usual pattern is mounted upon the said platform 1 and a power shaft 4 is journaled for rotation upon the said platform. A crank arm 5 is fixed to the shaft 4 and one end of a link 6 is pivotally connected with one end of the said crank arm and the other end of the said link 40 is pivotally connected with one end of a walking beam 7 which in turn is pivoted upon the upper end of the samson post 2. A sheave pulley 8 is journaled for rotation at the outer end of the walking beam 7 and a sheave pulley 9 is journaled for rotation at the intermediate portion of the said walking beam 7 and also at the upper end of the samson post 2. A shaft 10 is also journaled at one end upon the platform 1 and at its other end in an eccentric or stub shaft 11^a having a lever 11. One end of an operating rod 12 is pivotally connected with the eccentric lever 11 and the other end portion of the said rod 12 passes through a guide 13 attached to the platform 1 and located in the vicinity of the end of the said platform.

The rod 12 is slidably received in the guide 13 and the said rod in the vicinity of its end is provided with a series of notches 14 which are adapted to engage the guide 13 whereby the said rod is restrained against longitudinal movement through the guide. A friction disk 15 is fixed to the intermediate portion of the shaft 10 and a friction disk 16 is fixed to the intermediate portion of the shaft 4. The friction disk 15 at times is adapted to be brought in frictional contact with the periphery of the disk 16. A winding drum 18 is mounted upon the shaft 10 and is adapted to rotate with the same upon 70 the eccentric lever 11.

A relatively short cable 19, preferably formed from wire is provided at one end with a clamping device 20 and the said cable is trained over the pulley sheaves 8 and 9, 75 thence down under a pulley sheave 21 journaled upon the platform 1 and thence is arranged to wind upon and unwind from the drum 18. A brake block in the form of a shoe 23 is mounted upon the platform 1 adjacent the periphery of the friction disk 15. A rod 24 is secured at one end to a post 25 mounted upon the platform 1 and the said rod passes transversely through the upper portion of the block or shoe 23 and is 80 held in an adjusted position by means of a nut 26 which is screw-threaded upon the end of the said rod and bears against the side of the said block or shoe 23.

From the above description it will be seen 90 that as the walking beam 7 is oscillated upon its pivotal support at the upper end of the samson post 2 the outer end portion of the comparatively short cable 19 will be reciprocated vertically and by the connecting clamp 20 the cable 22 will be moved correspondingly. When it is desired to lengthen or shorten the cable 19 in order that the tool carried by the cable 22 may be raised or lowered in the well being drilled 100 an operator will manipulate the rod 12 to move the same longitudinally. When it is desired to raise the tool within the well the rod 12 is moved so that the eccentric lever 11 is swung about the axis of the 105 shaft 10 and the eccentric or stub shaft 11^a carried thereby is turned so that the periphery of the friction disk 15 is carried away from the brake block 23 and is moved into engagement with the periphery of the 110 friction disk 16. Inasmuch as the said friction disk 16 is rotating in unison with

the shaft 4 the said friction disk 15 will be turned and the drum 18 will be rotated whereby the cable 19 is wound upon the said drum. In order to lower the tool in 5 the well the operator moves the rod 12 so that the eccentric lever 11 is turned in the reverse direction to that just above described whereby the periphery of the friction disk 15 is brought into engagement with the 10 brake block or shoe 23. This holds the said friction disk 15 and its attached drum at a state of rest. Then by permitting the said disk 15 to slip against the face of the block or shoe 23 the cable 19 may unwind from 15 the drum 18 and thus the tool carried by the cable 22 is permitted to lower into the well. Therefore it will be seen that a simple and an effective drill rig is provided which may be manipulated to shorten the cable 19 20 as the cable 22 is being raised in the hole and thus when it is desired to adjust the cable 22 in length with relation to the cable 19 and prior to stopping the operation of the drill rig the operator may permit the 25 cable 19 to wind upon the drum 18 and thus the tools are elevated above the bottom of the hole and consequently cannot become wedged by the chips sanding in or becoming located between the sides of the said tool 30 and the sides of the hole. At the same time, during the drilling operation all of the advantages are had which are incident to relying upon the strength of the cable 22 during its downward movement in order to 35 bring the lower end of the tool in forcible contact with the bottom of the hole.

Having described the invention, what I claim as new and desire to secure by Letters Patent is:

- 40 1. In a drill rig, the combination of a 100 platform, a shaft extending transversely thereof, bearings disposed upon said platform, one of said bearings directly supporting one end of said shaft, a winding 105 drum secured to said shaft adjacent the just mentioned end, a stub shaft rotatably mounted in the other of said bearings and provided with a bore extending partially therethrough, the said bore being formed 110 eccentrically with respect to the axis of said stub shaft, the bore of the said stub shaft receiving therein the other end of the first mentioned shaft, and a lever formed integral with the outer extremity of said 115 stub shaft adapted to oscillate the same, to thereby shift one end of the first mentioned shaft, a driving friction disk, a brake shoe, a friction disk secured to the said first mentioned shaft and adapted to contact with 120 the said driving friction disk and the said

brake shoe, a samson post secured to said platform, a walking beam supported thereabove, a cable wound upon said drum and extending over said walking beam adapted to reciprocate a drill by the movement of 65 said walking beam.

2. In a drill rig, the combination of a 70 platform, a samson post secured thereto and extending upwardly therefrom, a rod pivotally secured to the upper end of said samson post, a walking beam with spaced side walls fulcrumed upon said rod, a pulley rotatably mounted upon said pivoted rod disposed between the side walls of said walking beam, a pulley rotatably secured to the 75 outer extremity of said walking beam, a driven shaft extending transversely of said platform and beyond the edges of the same, a crank arm rigidly secured to one extremity of said shaft, and a pitman connecting the 80 said crank arm and the inner extremity of said walking beam, the said walking beam extending at an angle to the longitudinal axis of the said platform to bring the inner end of the same directly above said crank 85 arm, a second shaft extending parallel to the first mentioned shaft and provided with a winding drum adjacent one end thereof, a friction disk adjacent the other end of said second mentioned shaft, a stub shaft mounted 90 for rotation and provided with a bore extending partially therethrough, said bore formed eccentric with respect to the axis of said stub shaft, said bore adapted to receive therein the end of said second mentioned shaft adjacent the friction disk, a lever rigidly secured to the outer extremity of said stub shaft and adapted to rotate the same to thereby shift the end of said second mentioned shaft, a friction disk rigidly 100 secured to the first mentioned shaft, a brake shoe secured to said platform, said friction disk mounted upon the second mentioned shaft adapted to be moved into contact with said friction disk and with said brake shoe, 105 and a cable wound upon said drum and extending over the said samson post pulley and the walking beam pulley and secured to a drill adapted to reciprocate the same by a movement of said walking beam, and a 110 notched lever secured to said stub shaft lever adapted to hold the same in any desired position.

In testimony that I claim the foregoing as my own, I have hereto affixed my signature in the presence of two witnesses.

LEWIS WORTHINGTON APPLEMAN.
